UNITED STATES PATENT OFFICE

98,897

DESIGN FOR AN AUTOMOBILE TIRE OR SIMILAR ARTICLE

George D. Storrs, Eau Claire, Wis., assignor to Gillette Rubber Company, Eau Claire, Wis., a corporation of Wisconsin

Application January 18, 1936, Serial No. 60,651

Term of patent 14 years

To all whom it may concern:

Be it known that I, George D. Storrs, a citizen of the United States and a resident of the city of Eau Claire, county of Eau Claire, and State of Wisconsin, have invented a new, original, and ornamental Design for an Automobile Tire or Similar Article, of which the following is a specificcation, reference being had to the accompanying drawing, forming a part thereof.

On the drawing:

The figure is a perspective view of the automobile tire, partly in dotted lines, showing my invention.

I claim:

The ornamental design for an automobile tire or similar article as shown.

GEORGE D. STORRS.
